(57) CLAIM

The ornamental design for a wall-mounted charger as shown and described.

DESCRIPTION

FIG. 1 is a front elevational view of a wall-mounted charger showing our new design;

FIG. 2 is a rear elevational view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof; and,

FIG. 8 is another perspective view thereof.
